TURNBUCKLE WRENCH

James Herbert Dye, Bainbridge, Ga.

Application August 3, 1943, Serial No. 497,211

3 Claims. (Cl. 81—13)

This invention relates to wrenches and more particularly to a turnbuckle wrench.

An object of this invention is to provide a tool which is particularly designed for working on airplanes in confined places which is adapted to straddle a turnbuckle to hold the threaded bolts against turning so that one hand may be used to hold the two bolts against turning while the other hand may be used to tighten or loosen the turnbuckle. In practice, a very small opening is provided in airplane wings or bodies through which access may be had to certain turnbuckles which are connected to cables and it is almost impossible to extend both hands through the opening, hold the aligned bolts against turning and at the same time adjust the turnbuckle. However, with a tool constructed according to this invention the handle may be made long enough to project through the opening, the working end of the tool firmly holding the bolts against turning, and permitting the extension of only one hand through the opening for adjusting the turnbuckle.

Another object of this invention is to provide a tool of this kind which is simple in construction and will greatly facilitate the performance of the work for which the tool has been constructed.

In the drawing:

Figure 1 is a side elevation of a turnbuckle wrench constructed according to an embodiment of this invention;

Figure 2 is a detail side elevation of the tool;

Figure 3 is a fragmentary sectional view taken on the line 3—3 of Figure 1.

Referring to the drawing the numeral 10 designates generally a handle which, in the present instance, is constructed out of a single piece of relatively stiff wire, being formed of outwardly convergent sides 11 and parallel forward portions 12 which are welded or otherwise secured together, as indicated at 13. The forward ends of the parallel extensions 12 have formed integral therewith oppositely extending right angularly disposed branches 14 and 15, and the outer ends of the branches 14 and 15 have formed integral therewith right angularly disposed extensions 16 and 17. The extensions 16 and 17 are of arcuate configuration and the extension 16 has secured thereto a nut engaging socket 18 which is open as at 19. The extension 17 has secured thereto a nut engaging socket 20 which is similar in every detail to the socket 18 and preferably the sockets 18 and 20 are not only in alinement but open on an acute angle with respect to the length of the handle 10, as shown in Figure 2.

In an airplane construction the cables which are used for various movable elements, such as the ailerons, rudder, and elevators are held in taut condition by means of one or more turnbuckles and at least certain of these turnbuckles are positioned to normally be disposed within the area of a relatively small opening which is covered by a removable plate, the opening being either in a wing or other closed part of the airplane. In order to adjust the turnbuckle it is necessary for the workman to hold the threaded bolts at each end of the turnbuckle against turning and then rotate the turnbuckle. As the hands of the workman have to be extended through the small opening which is frequently too small for two hands to be extended therethrough, it is a difficult operation to accurately adjust the turnbuckle to either tighten or loosen the desired cable.

The tool herein described is of such construction that the two sockets 18 and 20 may be extended through the small opening and the handle 10 is of sufficient length so that it will project outwardly of the opening and may be held by the hand exteriorly of the opening. As shown in Figure 1, the socket members 18 and 20 are adapted to be engaged with the nut bodies 21 and 22, which are carried by reversely threaded bolts 23 and 24 respectively. The bolts 23 and 24 are fixed in any suitable manner to the adjacent ends of cables 25 and 26 and a turnbuckle 27, which is formed with oppositely threaded bosses 28 and 29 is adapted to be threaded onto the bolts 23 and 24. The nut portions 21 and 22 of the bolts 23 and 24 respectively may be square in transverse section, or may be of any other suitable configuration, and it will, of course, be understood that the sockets 18 and 20 are of a configuration similar to the configuration of the nuts 21 and 22.

In the use and operation of this tool, the sockets 18 and 20, together with the arms 14 and 15, are extended through the small opening, and then engaged with the nuts 21 and 22. The handle 10, preferably projects outwardly of the opening so that it may be grasped by one hand of the workman. The other hand of the workman may then be extended through the opening and engaged with the turnbuckle 27 which may be turned to either tighten or loosen the cables 25 and 26. This tool is of exceedingly simple construction and will greatly facilitate the adjustment of various cables which are adjusted in confined places and provides a means whereby the end of one cable will be held against rotation with respect to the adjacent end of the connected

cable so that the cable will not twist and the workman can be assured that any adjustment of the turnbuckle will effect a similar adjustment of the connecting cables.

At the present time, while the workman can apply a wrench to one of the nuts carried by the turnbuckle bolts, the nut on the other turnbuckle bolt cannot be held against rotation so that it frequently happens that turning of the turnbuckle by the other hand of the workman will twist the unsecured cable and during the operation of the plane this torsional strain on the cable will have a tendency to rotate the turnbuckle and throw the cables out of their proper adjustment.

With a tool constructed according to this invention the two cable ends are not subjected to any torsional strain so that adjustment of the turnbuckle will not put any torsional strain on the cables and the adjustment of the turnbuckle will remain fixed.

I claim:

1. A turnbuckle wrench comprising a handle formed of a rod bent upon itself to form a loop

having forwardly convergent straight sides, parallel side by side extensions extending from the convergent ends of said sides, outwardly extending arms integral with and disposed at right angles to said extensions, forwardly extending rearwardly directed extensions integral with said arms, and rearwardly facing socket members carried by said latter extensions.

2. A turnbuckle wrench having a handle formed out of a single length of stiff wire bent upon itself to form a loop, the said loop having outwardly convergent sides and parallel forward portions, the said portions being secured together, integral oppositely extending right angularly disposed branches extending from said parallel forward portions, integrally formed right angularly disposed extensions of arcuate configuration extending from the ends of said branches, and nut engaging sockets secured to the said arcuate extensions.

JAMES HERBERT DYE.
